UNITED STATES PATENT OFFICE

EDWARD B. SOMERS, OF DARBY, PENNSYLVANIA, ASSIGNOR TO TYBON CORPORATION, OF CAMDEN, NEW JERSEY, A CORPORATION OF NEW JERSEY

RIBBONER

Application filed March 23, 1928. Serial No. 264,019.

My invention relates to reeling mechanisms for winding typewriter ribbons from larger rolls.

One of the purposes of my invention is to provide simple and effective means to measure the length of ribbon wound, to give a signal when this length has been wound and to permit quick and easy variation in the setting of the length at which the signal is to be given.

Further purposes will appear in the specification and in the claims.

I have preferred to illustrate one structure only among a number in which my invention might be embodied, selecting a form which is simple, practical, reliable and inexpensive and which at the same time well illustrates the principles involved.

Figure 1 is a longitudinal section corresponding to line 1—1 in Figure 2.

Figure 2 is a section of Figure 1 taken upon line 2—2.

Figure 3 is a section of Figure 2 taken upon line 3—3.

Figures 4 and 5 are perspective views showing parts seen in Figures 1 and 2.

Figures 6 and 7 are fragmentary enlarged sections of the structure shown in Figures 1 and 2 taken upon line 6—6 of Figure 2 and 7—7 of Figure 1, respectively.

In the drawings similar numerals indicate like parts.

My winding mechanism is conveniently mounted upon any suitable frame which is here shown as comprising a base plate 10, hollow to hold part of the mechanism, and a top or cover 11, 11' made in two parts for convenience of access.

The reeling mechanism is most conveniently attached to a rigidly supported part of the case and the measuring mechanism is most conveniently supported from the base, but these relations are not essential. As shown I attach the ribbon roll support to the member 11 by a bracket 12. The support itself is in the form of a preferably stationary backing or braking member 13 and a projecting center pin 14 about which the roll 15 is adapted to turn as the ribbon 16 of the roll is drawn from it by rotation of the spool 17.

The ribbon roll 15 will of course be of different widths according to the width of the ribbon used upon the typewriter which it is intended to fit, but all of these widths may be accommodated in the mechanism shown. 55

In order to apply pressure to the sides of the roll so as to give the desired friction against unwinding I clamp the roll between the surface of braking member 13 and the surface of a second braking member, cover 60

18. The cover protects additionally against soiling of the ribbon at the same time that it performs the clamping or braking function.

It is quite desirable that the braking be 65 resilient and that it be adaptable to ribbons of different widths. These aims are secured by recessing the cover 18 at several points about its circumference as at 19, 19', 19² in such a way that it may engage to different extents with fingers 20 which are resilient in 70

a direction transverse to the braking surfaces. The fingers are located at the free ends of springs 21 whose inner ends are rigidly fastened to the plate by any suitable means such as by strips 22. The springs diverge 75 from the plate at their outer ends to give the required resilience between the fingers and any suitable recess faces 23 on the cover.

To provide for variation of the "set" distance between the two braking surfaces I 80 therefore utilize a series of stepped faces 23, 23', 23² and 23³ for engagement with spring fingers 20 so that the attachment is varied by the extent to which the cover 18 is turned after engagement with the fingers begins. 85

The introduction to the first face 23 and the recess surfaces between successive faces are sloped as at 24 so as to make it possible conveniently to apply the cover against the 90

spring in any of the adjusted positions by merely passing the cover openings 19, 19', 19² over the spring fingers and then rotating the spring in a direction which would be clockwise as shown in Figure 1 and counter clockwise as shown in Figure 5.

In addition to the openings leading to the stepped surfaces 23, 23', etc., the cover is cut at 25 throughout a space large enough to provide for outward passage of the ribbon 16 100

from the roll in any of the positions to which the cover has been turned.

As the ribbon passes out from the supporting mechanism it belts about a drum 26, supported to rotate upon or about a stub shaft 27. It then passes between a curved guide 28 and a guard 28' and thence into engagement with the spool 17 upon which it is being wound. The drum is interposed for the purpose of providing a measure and indicator or alarm so as to permit preliminary setting of the length of ribbon which is being wound upon the spool.

The ribbon spool 17 is mounted upon a preferably rotatable shaft 29 which is supported wholly from the one side of the spool by a fitting 30. This fitting forms a bearing for the shaft if the shaft be rotatable. The shaft is surrounded by a gear 31 which revolves about the shaft at the same rate as a spool-driving abutment 32. Gear 31 is driven by a gear 33 mounted upon a rotatable shaft 34 turned by crank 35 and handle 36. The shaft 29 and driving shaft 34 are supported in the fitting 30 where they are retained by nuts 37, 38. The fitting is held to the casing in any suitable manner.

The shaft 29 is threaded at 39 to provide for mounting upon it any suitable engaging device 40 and nut 41. The engaging device is shown as a cone. It should be of suitable form to center the spool 17 and to press the spool against the abutment (disc) 42 which is driven by the gearing.

The rotary abutment 42 is preferably so far the driver that it makes little difference whether the engaging device 40 (and, therefore, the shaft 29) rotate or not.

In order to provide for rapid mounting and removal of the spools, the nut 41 is split and coned at its inner end. Its cone face 43 enters a recess 44 within the engaging device 40. When the inner end is free from engagement of the cone with the walls of the recess the sides of the nut separate and release the nut from the thread permitting quick removal of the nut and of the engaging device 40 so that the spool can be placed or withdrawn. A ribbon spool is placed over the free end of the spindle, the engaging device is put in place against it and the nut is passed over the shaft and its cone is pressed into contact with the engaging device. The ends of the nut will then be contracted upon the thread and the nut can be screwed to place as tightly as may be desired. For removal, the nut is screwed back until its split ends release from the thread and the nut and engaging device are then slid free from the shaft.

The drum 26 carries a face gear 45 which operates an indicating and alarm system. The face gear 45 engages a gear 46 which carries with it a finger 47 adapted to engage and subsequently release an arm 48. The arm is retracted by a spring 49 fastened upon any

suitable post 50. The arm carries a hammer 51 which strikes a bell 52 when the spring-retracted arm is released.

Concentric with gear 46 I mount a fixed indicator 53 upon which yard notations are marked in the reverse order of the direction of movement of the gear, beginning from a zero point corresponding with the point at which the projection 47 releases arm 48. As a result if the gear 46 be turned to any position, such as that in which the indicator is opposite the number 10 it would show that a corresponding number of yards—10—would be wound upon the spool before the alarm would strike.

In order that the counting mechanism may be set to give an alarm for any desired number of yards to be wound upon the spool, the mount for the gear 46 is so arranged that it can be swung away from the face gear 45 to permit turning of the gear 46 to any desired angular position to correspond with any desired number of yards to be wound before signal is given of completion of this extent of winding.

The mechanism by which the gear 46 can be tilted away from face gear 45 is extremely simple. The spindle 54 upon which the gear 46 turns is carried by an arm 55 pivoted at 56 and pressed by spring 57 toward the face gear. Withdrawal from the face gear means merely movement of the spindle 54 in a clockwise direction in Figure 6 against the strength of the spring 57. It would of course be objectionable to have the strength of spring 57 normally pressing the gear 46 against the face gear 45 as this would cause excessive depth of engagement of the gears or excessive friction of the outer faces of the teeth upon gear 46 against the support upon which the face gear is mounted. This objection is avoided by the use of a screw 58 threaded into the base 10 and locked by a nut 59. The screw presses against an abutment 60 carried by the arm 55, whereby the swinging movement of the gear can be stopped with just the right amount of engagement between the gears.

In operation, the gear 46 is drawn away from the face gear 45 while gear 46 is being turned to bring the projection 47 opposite that number upon a scale 53 which represents the number of yards desired. The gear 46 is then released to engage with the face gear.

The ribbon roll is mounted upon spindle 14 and is threaded beneath and about the drum. It is then turned upwardly over guide 28 to the spool. The inked tape is fastened to the spool core and the ribbon is wound upon the spool until the bell rings, indicating the proper length of ribbon wound. The ribbon is then cut, preferably between the guide 28 and the spool. The completely wound ribbon and spool are then withdrawn.

In view of my invention and disclosure va-

riations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention what I claim as new and desire to secure by Letters Patent is:

1. In mechanism for rewinding ribbon from a roll, a drum adapted to be rotated by the ribbon, a face gear carried by the drum, a gear engaging the face gear and spring-pressed against it and movable away from it to permit withdrawal from its engagement and resetting of the gear, an alarm operated by movement of the gear and fixed indicating means cooperating with the gear to indicate the extent of ribbon to be wound before operation of the alarm.

2. In mechanism for rewinding ribbon from a roll, a drum adapted to be rotated by the ribbon, a face gear carried by the drum, a gear engaging the face gear and spring-pressed against it, permitting withdrawal from its engagement and resetting of the gear, an adjustable stop for limiting the depth of engagement of the second gear with the face gear, alarm and connections to the alarm operated by movement of the second gear.

3. In mechanism for rewinding ribbon from a roll, a drum rotated by the material rewound, a gear rotating with the drum, an alarm, a gear operating with the alarm and connections between the two gears, permitting disconnection and resetting of the gears to set off the alarm with different lengths of winding.
